UNITED STATES PATENT OFFICE

2,429,572

TEMPERATURE ALARM

Andy H. Visocan, Raynesford, Mont.

Application October 1, 1945, Serial No. 619,539

2 Claims. (Cl. 200—140)

1

This invention relates to a temperature alarm which is particularly adapted for use in connection with a brooder or an incubator, it being understood that the alarm may be used in hot-houses, or wherever it is desired to provide an alarm which will be energized when a predetermined variant in desired temperature has taken place.

One object of the invention is to provide an alarm mechanism including contacts carried by strips which are mounted so that one may move toward the other, movement of the movable strips being controlled by a thermostat so that when the temperature within a brooder or the like is reduced to such a point that there is danger of small chickens being chilled, an alarm will be sounded to attract the attention of a person having charge of the brooder.

Another object of the invention is to provide a circuit closing device so constructed that it may be adjusted and set for a predetermined temperature, provision being also made to cause a circuit through an alarm to be closed when a predetermined variation in temperature occurs.

Another object of the invention is to provide a circuit closer consisting of a comparatively few number of parts, all of which are of simple construction and not liable to get out of order. The invention is illustrated in the accompanying drawing, wherein:

Figure 1 is a top plan view of the improved alarm.

Figure 2 is a side view thereof.

Figure 3 is a view looking at the device from one end.

Figure 4 is a sectional view taken along the line 4—4 of Figure 2, and

Figure 5 is a sectional view taken along the line 5—5 of Figure 2.

This alarm device or circuit closer has a base 1 which may be formed of hard rubber or other suitable insulating material. Intermediate its length the base is formed with a step 2 in order to dispose the end portion 3 of the base in a plane below the level of the remainder of the base. This base may be mounted in any desired manner in order that it may be supported in an incubator or brooder. A bracket 4 having downwardly bent portions 5 terminating in seat 6 is secured transversely of the base adjacent one end thereof by screws or equivalent fasteners 7, and to this bracket is secured a strip 8 which extends longitudinally of the base in vertical spaced relation thereto. The inner end portion of the strip 8 is free and upon this end portion of the

strip is mounted a contact 9 which projects upwardly therefrom. The strip 8 and the bracket 4 are formed of conductive material and at least one of the fasteners 7 extends downwardly through the base to form a terminal to which a conductor wire is adapted to be secured by a nut 9'. In case the base should be formed of material of a conductive nature, the bracket 4 and its fastener 7 may be insulated from the base 10 by washers 10 formed of insulating material.

Posts 11 which are formed of metal are disposed vertically near side edges of the base, one post being screwed into a block or socket 12 carried by the base and the other being passed through 15 a block 13 and through an opening 14 formed in the base and registering with the bore of the block 13.

The elongated post has its lower portion projecting downwardly to form a terminal with 20 which a second conductor wire may be secured by a nut 15. It should be noted that these posts are insulated from the block by bushings 16 and 17 formed of insulating material. Above the blocks 12 and 13, the posts pass through 25 spacing sleeves 18 and carry a cross-bar 19 which is held upon the spacer by nuts 20. The cross-bar or bridge 19 is circular in cross section, as shown in Figure 2, and upon this cross-bar is mounted a hanger bracket 21. The hanger bracket is formed integral with the inner end 30 of a strip 22 formed of conductive material, against the under face of which is mounted a contact 23.

Referring to Figures 2 and 4, it will be seen 35 that the contact 23 is disposed directly above the contact 9. Therefore, when the strip 22 is flexed downwardly, the contact 23 may be brought into engagement with contact 9 and a circuit will be closed through the conductor wires attached to 40 the terminal portions of the fasteners 7 and 11 and cause a bell to ring or warning light to be illuminated and thus attract attention of an attendant instead of allowing the temperature to be lowered to such a point that small chickens 45 in a brooder will be killed or eggs in an incubator caused to become chilled to such an extent that they will not hatch. Cotter keys 24 are passed through openings formed in the cross-bar or bridge 19 and serve to prevent the bracket 21 from shifting along the cross-bar to such an extent 50 that the contact 23 carried by strip 22 will be out of position to make contact with the contact 9.

In order to control movement of the strip 22, 55 there has been provided a thermostat 25 of the bel-

lows type. This thermostat has a depending neck 26, into which engages the upper end of a threaded post or screw 27 which passes through a threaded opening formed in the depressed portion 3 of the base and carries a lock nut 28 for securing the post or screw in a vertically adjusted position. A threaded post 29 extends upwardly from the thermostat through an opening formed near the outer end of strip 22 which is firmly held in place about post 29 by a nut 30. A bushing 31 of insulating material prevents direct engagement of strip 22 with post 29 and thus eliminates the likelihood of a short circuit at this point. By adjusting the post 27 vertically, the contact 23 may be spaced upwardly from contact 9 such a distance that the contact 23 cannot have engagement with contact 9 until the thermostat has contracted to a predetermined extent, and since this contraction of the thermostat is caused by lowering of temperature in a brooder or incubator, the operator of the brooder or incubator may set the device to permit predetermined lowering of the temperature before an alarm will be sounded. When a brooder is equipped with the improved signal, danger of small chickens being chilled by the temperature becoming too cold will be eliminated.

It is thought that persons skilled in the art to which the invention relates will be able to obtain a clear understanding of the invention after considering the description in connection with the drawings. Therefore, a more lengthy description is regarded as unnecessary.

Minor changes in the shape, size and arrangement of details coming within the field of invention claimed may be resorted to in actual practice, if desired.

What is claimed is:

1. A circuit closer for a temperature signal comprising a base, a bracket carried by said base, a strip carried by said bracket and extending longitudinally of said base in vertical spaced relation thereto, posts mounted vertically adjacent opposite side edges of said base forwardly of said bracket, a bridging bar extending between said posts and having its ends formed with openings through which said posts pass, a hanger bracket under said cross-bar having upstanding arms through which the cross-bar passes to pivotally mount the hanger bracket, a strip extending from said hanger bracket over the first strip, contact carried by confronting faces of said strips, one above the other, a post adjustably mounted through said base adjacent the front end thereof, a thermostat carried by the upper end of said post, a neck projecting upwardly from said thermostat and passing through an opening near the

forward end of the last-mentioned strip, and a fastener firmly securing the last-mentioned strip to said neck.

2. A circuit closer for a temperature alarm comprising a base carrying one end portion offset downwardly, a bracket carried by said base, fasteners for said bracket passing through said base and one constituting a terminal adapted to have a conductor wire secured thereto, a strip of conductive material carried by said bracket and extending longitudinally of said base in spaced relation thereto, blocks carried by said base adjacent opposite side edges thereof forwardly of said bracket, posts carried by said blocks, one of said posts extending downwardly through the base and adapted to have a conductor wire connected therewith, a cross-bar extending between said posts and formed near its end with openings through which the posts pass, spaces about said posts between said blocks and ends of said bar, fasteners screwed upon upper end portions of said posts and holding said cross-bar against said spaces, a hanger bracket suspended from and pivotally carried by said cross-bar between said posts, pins passing through said cross-bar to prevent shifting of the hanger bracket longitudinally of the cross-bar, a strip of conductive material extending from said hanger bracket longitudinally of said base over the first strip, contacts carried by confronting faces of said strip in opposed relation to each other, a threaded post passing upwardly through a threaded opening formed through the offset forward end portion of said base, a set-screw carried by said threaded post for securing the threaded post in a vertically adjusted position, a thermostat having a depending, internally threaded socket screwed upon the upper end portion of the threaded post a threaded neck projecting upwardly from said thermostat through an opening near the forward end of the second strip, and a nut screwed upon said neck and engaging the second strip to firmly hold the same upon said neck.
